(57) **CLAIM**

The ornamental design of a tissue maintenance and assessment device tissue container as shown and described.

DESCRIPTION

FIG. 1 is a perspective view of the tissue maintenance and assessment device tissue container, showing a tissue container of our new design;

FIG. 2 is a rear side elevational view thereof;

FIG. 3 is a front side elevational view thereof;

FIG. 4 is a left side elevational view thereof;

FIG. 5 is a right side elevational view thereof;

FIG. 6 is a top plan view thereof; and,

FIG. 7 is a bottom plan view thereof.

1 Claim, 7 Drawing Sheets
